UNITED STATES PATENT OFFICE.

STEPHEN H. FARNHAM, OF BROOKLYN, AND ARTHUR W. SMITH, OF NEW YORK, N. Y.,
AND JOSEPH PHELPS, OF BELLEVILLE, NEW JERSEY, ASSIGNEES TO REMINGTON
TYPEWRITER COMPANY, OF ILION, NEW YORK, A CORPORATION OF NEW YORK.

TYPE-WRITING MACHINE.

1,217,290.

Specification of Letters Patent. Patented Feb. 27, 1917.

Original application filed January 18, 1913, Serial No. 742,786. Divided and this application filed May 13, 1913. Serial No. 767,203.

To all whom it may concern:

Be it known that we, STEPHEN H. FARNHAM, ARTHUR W. SMITH, and JOSEPH PHELPS, citizens of the United States, and residents, respectively, of the borough of Brooklyn, county of Kings, city and State of New York; borough of Manhattan, city, county, and State of New York, and Belleville, county of Essex, and State of New Jersey, have invented certain new and useful Improvements in Type-Writing Machines, of which the following is a specification.

Our present invention relates to line spacing or paper advancing mechanism for type-writing machines and its chief object is to provide new and improved mechanism of the character specified.

To the above and other ends our invention consists in the features of construction, combinations of devices and arrangements of parts hereinafter described and particularly pointed out in the claims.

This application is a division of our prior application, Serial No. 742,786, filed January 18, 1913, now Patent No. 1,071,612, granted August 26, 1913. The present invention is applicable in whole or in part to typewriting machines generally, although the preferred embodiment of it herein disclosed was particularly designed for line spacing and controlling the work sheets on both the main and sub-carriages of the typewriting machine disclosed in said prior application.

One form of our invention is illustrated in the accompanying drawings, wherein—

Figures 1 and 2 are respectively the front and rear portions of a fore and aft vertical sectional view of a typewriting machine embodying our invention, only so much of said machine being shown as is necessary to a full understanding of said invention.

Fig. 3 is a fragmentary right-hand end view of the upper part of said machine, parts being omitted and parts being broken away.

Fig. 4 is a fragmentary view partly in section showing a portion of a paper feed roller hereinafter described.

Fig. 5 is an end view of the main carriage, showing part of the line spacing or paper

advancing mechanism that is mounted on the sub-carriage.

Fig. 6 is a sectional view taken on a plane indicated by the dotted line *q—q* in Fig. 5 and looking in the direction of the arrow at said line.

Fig. 7 is a horizontal sectional view of the line spacing devices for turning or line spacing the platen, the section being taken on a plane indicated by the dotted line *p—p* in Fig. 10 and looking downward as indicated by the arrow.

Figs. 8 and 9 are views corresponding to Fig. 7 but showing some of the parts in different relationships.

Fig. 10 is a vertical sectional view taken on the plane indicated by the broken dotted line in Fig. 7 and looking in the direction of the arrow at said line.

Fig. 11 is a detached front view of the cam member shown in Fig. 7 and included in the line spacing or turning mechanism of the platen.

Figs. 12 and 13 are fragmentary end views of certain of the line spacing or paper advancing devices for the sub-carriage work sheet, said views corresponding to Fig. 3 but the positions of some of the parts being different.

Fig. 14 is a sectional view taken on planes indicated by the broken dotted line *m—m* in Fig. 12 and looking in the direction of the arrow at said line.

As shown in Figs. 1 and 2 the main frame of the machine comprises a base 1 from which rise posts 2, 3 and 4, the posts 3 and 4 at each side being connected by a web 5. Supported on the posts is a three-piece top plate comprising a rear part 11 and two front portions or plates 12. The machine is a front-strike machine and is provided with a stationary upright segment 13 on which are secured hangers 14 whereon are pivoted type bars 15 each provided with a type 16 and normally supported on a rest 17. Each type bar is connected to a key lever 18 by connections comprising a link 19, a lever 20 and a second link 21, said key levers being pivoted on a fixed fulcrum plate 22 and provided at their front ends with keys 23.

The type bars may print on superposed work sheets which are supported on main

and sub-carriages, the sub-carriage being mounted on the main carriage, the construction being set forth in detail in our prior application aforesaid. The main carriage 5 as appears in Figs. 1, 2 and 3 comprises end plates or bars 26 and 27, a front bar 28 and two rear bars 29 and 30. The bars 28 and 29 are grooved to coöperate through anti-friction balls 31 with stationary grooved guide 10 rails 32 and 33 which extend beyond the ends of the main frame as the main carriage is of a length to support a long platen 36 which is mounted on an axle 37 bearing in the end plates 26 and 27. A motor or spring 15 drum 39 pivoted to a stationary bracket 40 is connected to the main carriage by a strap 41 and leftward movements of said carriage are controlled by escapement devices comprising a feed rack 45 pivotally mounted on 20 the carriage and normally meshing with a feed pinion 49 operatively connected with escapement wheels 52 and 53 with which a feed dog 54 is adapted to co-act. Said dog is mounted on a rocker 55 pivoted at 56 to 25 ears 40^a on the bracket 40. Said rocker is operatively connected by a link 57 with a crank arm 58 fixed to a rock shaft 59 bearing in the base 1 and provided near its ends with crank arms 60 which support links 61 30 carrying a universal bar 62 underlying the key levers 18 and operative thereby.

The paper feeding devices for the platen 36 comprise a spring pressed releasable main feed roller composed of sections 92, 35 each having a shaft 93 which bears on arms 94 supported on a rock shaft 95; and further include a paper deflector 106 which is also supported from said rock shaft 95. A pressure device comprising rollers 130 coöper- 40 ates with the front upper side of the platen 36.

Referring now more particularly to the novel subject-matter covered by the present application, in order to control the line space 45 advance of the sheet or sheets on the platen 36, line spacing devices are provided which, as illustrated in Figs. 2, 3 and 7 to 11 inclusive, comprise a line spacing ratchet wheel 149 contiguous to the right-hand end 50 of the platen and suitably secured to the platen axle 37. Said ratchet wheel has both peripheral and crown teeth and coöperative with the peripheral teeth is a roller detent 151 mounted on a spring arm 152 secured 55 to the main carriage. Said detent operates to maintain the platen 36 in predetermined line space positions. To advance the platen step-by-step through line space distances, hand controlled pawl devices are provided 60 comprising an upright shaft 154 which bears near its upper end in a lateral ear 27^a on the right-hand carriage end bar 27, the lower end of said shaft bearing in an angular bracket 155 secured to said end bar 65 27. The upper end of the shaft 154 is

reduced and has pinned to it a line space lever or handle 156 which prevents the shaft from dropping out of its bearings, while a member or crank arm 157 fixed by a set screw 158 to the lower end portion of the 70 shaft which projects below the bracket 155 prevents upward displacement of said shaft. The shaft 154 is under constant tension from a spring 159 coiled around its upper portion. One end of said spring is anchored to 75 the ear 27^a while the other end is secured in an adjustable sleeve 160, the lower face of which is provided with ratchet teeth that coöperate with corresponding ratchet teeth on a collar 161 fast on said shaft. The 80 spring 159 tends constantly to turn the shaft in the direction of the arrow in Fig. 7. Rigid on the collar 161 is an actuator or 85 arm 162, the free end of which is rounded and engages in a slot 163 in a pawl 164, said pawl extending forward and terminating in a tooth which operatively engages during forward movements with the crown teeth of the ratchet wheel 149 at a point under the platen axle. Said pawl is pivoted at 165 on 90 an arm or carrier 166 which is provided with a hub or sleeve 167 that bears loosely on the shaft 154, being confined between the collar 161 and a collar 168 pinned to said shaft below said hub. The arm 166 and the 95 actuator 162 extend inward through a slot 169 in the end bar 27 and at substantially right angles to the line space lever 156 which extends forward above and to the right of said end bar. A spring 170 coiled around the hub 167 engages at one end with the outer face of the end bar 27 while its other end is connected to a pin 171 projecting downward from the arm 166. The spring 100 tends constantly to turn said arm rearward and normally maintains it engaged with an adjustable screw stop 172 supported on the end bar 27 as shown in Figs. 3 and 7. The spring 159 normally maintains the actuator 162 engaged with an upstanding 110 stop pin 173 on the arm 166, and so positions the pawl normally (Fig. 7) that it is out of the path of the ratchet wheel 149. This stop pin 173 may be the continuation 115 above the arm 166 of the pin 171. In operation an initial backward movement of the hand lever 156 overcomes the spring 159, turns the shaft 154 and causes the actuator 162 to turn the pawl 164 on its pivot 165 with the result that the pawl tooth engages 120 with the ratchet wheel 149 as shown in Fig. 8. This initial operation, it will be observed, does not affect the arm 166 which remains in normal position. However, since 125 now the pawl 164 can no longer turn freely on its pivot any further forward swinging movement of the actuator 162 will be transmitted to the arm 166 which will swing forward. Consequently the pawl will be forced to advance forward bodily and will 130

operate to turn the ratchet wheel 149 and the platen 36 connected thereto. The turning or line space advance of the platen will continue until the pawl engages with a screw stop 174 on the end bar 27 which co-operates with the pawl to jam it into the ratchet wheel and prevent overthrow (Fig. 9). The parts are adjusted so that the advance or turning movement thus communicated to the platen is equal to two units of line space distance. On releasing the lever 156 the parts will be restored to the normal position (Fig. 7).

In addition to these line spacing devices provision is made for turning the platen 36 automatically during leftward movements of the main carriage by means which comprise a roller 175 pivoted on a shouldered screw 176 secured to a crank arm 157 near its outer end. Said roller is adapted to co-operate with a cam 177 carried by a slide 178 mounted adjustably on a toothed bar 179 secured to lugs 4* on the posts 4, the bar 179 extending transversely of the machine. The upper edge of the bar 179 is formed at letter space intervals with teeth 180 and these teeth co-operate with a tooth 181 on the slide or cam member 178. The slide is formed with lips or troughs at its top and bottom so that it partly embraces the bar 179 and cannot be detached therefrom except by being slid off it endwise. The tooth 181 is maintained in engagement with the teeth 180 by a bowed spring 182 carried by the slide and co-operative with the bottom face of said bar 179. The construction is such that by pressing upward against the slide its spring may be overcome and its tooth disengaged, and it may then be slid to desired positions along the bar so as to vary the location of the cam and its consequent point or time of co-action with the roll 175. A scale on the bar 179 is preferably provided to facilitate adjustment of the parts carried thereby. When during leftward movements of the carriage the roll 175 contacts with the cam 177 it will ride up said cam until arrested by a dwell or stop portion 177* in which the left end of the cam terminates. As a consequence the crank arm 157 carrying the roll will swing on its axis and the shaft 154 will be forced to turn counter to its spring 159, and the pawl 164 will engage with the ratchet wheel 149 to turn the platen, as when the handle 156 is operated. The parts are proportioned and arranged so that when the pawl is jammed into the ratchet wheel by the stop 174 to arrest the parts the roll 175 will be in engagement with the stop 177*, and since the roll can swing no farther about the shaft 154 it will act in co-operation with the end on part 177* as a stop to limit the leftward movement of the main carriage and also to prevent disconnection of the automatically

operating devices 175 and 178. Preferably the arm 157 is releasably connected with the shaft 154 so that the roller 175 may be rendered inoperative, if desired.

The sub-carriage which is supported for relative movement on the main carriage comprises, as appears from Fig. 2, a base plate 183 having upturned end portions 183*. Said sub-carriage underlies the cross bar 30 of the main carriage, said cross bar being formed with a groove 184 providing a track-way with which the base plate 183 is connected by roller bearing devices 185. The sub-carriage is provided with a lug 192 depending from the base plate 183 and said lug is connected by a cord 193 to a spring drum 194 which constantly impels the sub-carriage toward the right. To hold the sub-carriage against the pull of its spring drum 194 and set in proper relationship with the main carriage, detent devices are provided comprising a rack bar 198 on the main carriage and a co-operative releasable pawl or detent 200 pivoted at 201 on the sub-carriage.

The sub-carriage is provided with paper supporting and controlling devices comprising, as appears from Fig. 2, a downwardly extending basket which is secured to ears 206 on the plate 183 and is numbered 208. Above said basket is arranged a deflector or guide plate 224 secured near its ends to fingers 225 that are mounted on arms 227 which are fixed to a sleeve or hollow rock shaft 229. The ends of said shaft receive bushings 230 which bear in openings in angular plates 231 secured to the base plate 183. The arms 227 also provide bearings for a shaft 232 which carries a feed roller 233 that projects rearward through slots in the deflector 224. The roller 233 co-operates with a larger or main feed or pressure roller located behind the deflector 224 and comprising a sleeve 237 and a sheath 238. As will be understood from Fig. 4 there is fixed in each end of the tube 237 by a screw 239 a flanged bushing 240, the flanged end whereof is outside the tube and abuts against the associate end portion or bar 183* of the sub-carriage. Extending through the bushings 240 and secured in place by screws 239 are inner bushings of which the right-hand one 242 is shown, the same having a flange or enlargement outside the end bar 183*. Suitable detent devices are provided for the main feed roller 237, 238 comprising, as shown in Fig. 5, a detent ratchet wheel 243 rigid with the roller and a co-operating spring mounted roller detent 244. These detent devices control the feeding movements of the paper on the sub-carriage which passes between said main feed roller and the secondary feed roller 233 and is fed upward from the basket or container 208 over the face of the platen 36, said paper 130

being indicated at 482 (Fig. 5). Said feed rollers 233 and 238 are maintained in spring pressed coöperation by draw springs 247, the springs tending constantly to turn the 5 rocking frame comprising the shaft 229 and arms 227 toward the rear and maintain the feed rollers in engagement while the guide plate 224 on said rocking frame is normally maintained with its upper edge contiguous 10 to the platen 36. The swinging of said frame to control the deflector and feed rollers is performed by means and in the manner set forth in our said prior application, Serial No. 742,786 to which reference 15 may be had for a fuller description of the sub-carriage and its paper feeding and controlling devices.

Means are also provided operative from the main carriage for turning the sub-carriage feed roller 237, 238 to advance or retract at will the work sheet or sheets carried by the sub-carriage. Said means, as illustrated in Figs. 3, 4 and 12 to 14 comprise a squared shaft 265 which passes through said 20 feed roller and bears in the end bars 26 and 27 of the main carriage. Said shaft is adapted to transmit motion to the feed roller through the bushing 242 which, as shown in Fig. 4, has a depression 266 25 slightly larger in diameter than the greatest cross dimension of said shaft. Said depression, however, extends only partway through the bushing, leaving a bottom or web 267 which is formed with a squared hole 30 of slightly greater dimensions than the shaft 265 so that while the bushing may slide freely along the shaft 265 during endwise movements of the sub-carriage on the main carriage, yet in any of its positions rotary 35 motion communicated to the shaft 265 will be transmitted through the bushing 242 to the roller 237, 238, causing it to turn and advance or retract the paper in coöperation with the roller 233. The right-hand end 40 portion of the shaft 265 projects some distance beyond the end bar 27 and is provided with a knurled finger wheel 268 by which the feed roller 237, 238 may be turned back and forth for feeding and adjusting purposes. Arranged on the shaft 265 just outside the end bar 27 is a line spacing ratchet 45 wheel 269 provided with a hub 270 which receives a set screw 271 by which the ratchet wheel is fixed to the shaft. Coöoperative with 50 said ratchet wheel is a pawl carrying member or lever 272 provided with two pawl teeth 273 and 274 and also with a stop lug or finger 275. Said pawl member is pivoted at 276 on an arm or lever 277 which in turn 55 is pivoted on a shouldered screw 278 secured in the end bar 27. The arm 277 is provided with a restoring spring 279 having one of its ends hooked over a pin 280 on said arm and its other end anchored to a pin 281 on the 60 end plate 27. A washer 282 is arranged on 65

the shouldered screw 278 between the arm 277 and the spring 279, said spring coöperating with said washer to prevent displacement of the arm 277 rightward away from the end plate 27. Forward of its pivot 70 276 the lever 272 is connected to the lower end of a link 282 which extends upward and is connected at its upper end to a crank arm 283 fixed by a clamping nut 284 to the reduced rear end 285 of a rock shaft 286 that 75 extends horizontally forward above the end bar 27 and terminates in a handle or finger piece 287 which extends angularly downward forward of the entire carriage structure and of the top plate. The rock shaft 286 bears at its rear end in a bracket 288 secured to the end bar 27 and also bears in a housing 289 fixed to said end bar near its front end. The housing is bored out at 290 to receive a pawl spring 291, one end of which is anchored to the housing and the other end to a collar 292 rigid on the rock shaft and bearing in the housing at the forward end of the depression 290. The springs 291 and 292 tend to maintain the line spacing devices thus described in the normal positions shown in Fig. 3. By swinging the line spacing handle or lever 287 toward the right the shaft 286 is rocked and the crank arm 283 swung upward, said crank arm acting on the link 282 to swing the lever 272 on its pivot 276 independently of the arm 277 to the position indicated in Fig. 12. This movement brings the finger 275 into contact with the pin 280 and also swings the pawl tooth 273 into engagement with the ratchet wheel 269. During further turning of the lever 287 the upward pull of the link 282 will be transmitted through the lever 272 to the arm or lever 277, causing the latter 100 to swing upward on its pivot 278, bodily moving upward the lever 272 whose relationship with its support will not vary during the first portion of the upward swing thereof. As a result the pawl tooth 273 will 105 coöperate with the ratchet 269 to turn the feed roller 237, 238 a unit's distance as regulated by its detent devices and succeeding this movement the pawl tooth 274 which has been brought into engagement with the 110 ratchet wheel will, during the continuance of the upward swing of the parts, turn the ratchet wheel through another unit's distance, the parts being arrested finally and the line spacing movement determined by 115 the engagement of the finger 275 with the ratchet wheel as illustrated in Fig. 13. Thus an operation of the line space lever 287 communicates a line spacing movement equal to two units to the paper on the sub-carriage. It will also be understood that said lever 287 is operative to retract the main carriage and with it the sub-carriage toward the right at will so that said lever performs the double function of communicating pro- 120 125 130

gressive step-by-step line space movements to the paper on the sub-carriage and of retracting both carriages concurrently at each of such line spacing operations. On releasing the handle 287 the line spacing devices will be restored to normal position as described. In such normal position it will be observed that the pawl teeth 273 and 274 are disconnected from the ratchet wheel 269, leaving the shaft 265 free to be turned by the finger button 268.

Line spacing or paper feeding devices are also associated with the left hand end of the square shaft 265 as illustrated in Figs. 5 and 6. Said devices comprise a pinion 293 arranged on that portion of the shaft 265 which projects leftward beyond the end bar 26, said pinion being contiguous to the outer face of said end bar and being provided with a hub 294 which receives a set screw 295 by which the pinion is fixed to the shaft 265. The pinion 293 meshes with a larger pinion or gear wheel 296 which is rotatably mounted on a shouldered screw 297 projecting laterally from the end bar 26, the head of said screw being provided with the usual nick 298. The gear 296 has a hub portion 299 which bears on the shouldered screw and abuts against the head thereof. Mounted on said hub is a ratchet wheel 300 and a collar 301 which is provided with a series of squared peripheral teeth 302. The ratchet wheel 300 and collar 301 are driven on the hub 299 and are secured in fixed relationship to the gear wheel 296 by one or more pins 303. Engaging in a tapped opening 304 in the screw 297 is a headed shouldered screw 305 and arranged thereon between its head and the head of the screw 297 is a pawl carrier or lever 306, the shouldered portion of said screw 305 providing a pivotal bearing for said carrier 306. Above its pivot 305 the carrier 306 is broadened out and its top surface is formed in a curve 307 concentric with its pivotal axis and terminating at its ends in recesses or depressions 308 beyond which are stop lugs 309. The depressions 308 and the curved surface 307 are adapted to cooperate with a roller detent 310 mounted on a spring arm 311 which extends upward and is provided with a lateral off-set which receives a headed screw 312 by which the spring arm is secured to the end bar 26. A reinforcing washer or plate 313 may be arranged between the head of the screw 312 and the top portion of the arm 311. The carrier 306 provides a support for a double pawl member or device 314 which carries a pivot device or headed shouldered screw 315, the shouldered portion whereof engages in a bearing opening formed in the stem of the carrier 306 below its pivot. The pawl device or member 314 is spread or extended laterally above its pivot and terminates in

two pawl teeth 316 and 317 which are at opposite sides of the pivot and above the same. At its lower end the member or pawl device 314 is provided with an outwardly extending finger piece or handle 318. The pawl 314 is loose on its carrier 306 but is maintained in a normal central position by means comprising a pair of centering springs 319. These springs are arranged at opposite faces of the stem of the carrier 306 and at their upper ends are provided with ears 320 which are riveted or otherwise secured to the face of the carrier. The lower ends of the springs are free and are provided with inwardly extending lugs 321 which overlie the sides of the pawl 314 and maintain it in a middle position and so that its teeth 316 and 317 are disengaged from the squared teeth 302 of the collar 301 with which said teeth are adapted to coöperate. With the parts in the position shown in Fig. 5 it will be understood that if the finger piece 318 is pulled forward the forward spring 319 will be flexed, permitting the pawl 314 to turn on its pivot and the tooth 317 to engage between two of the teeth 302. This motion of the pawl 314 is independent of its carrier 306 but thereafter as the forward pull on the finger piece 318 is continued, said carrier will turn on its pivot concentrically with the collar 301 which will be forced to turn by the tooth 317. At the beginning of the movement of the carrier 306 the detent 310 will disengage from the rear depression 308 and will be forced up on to the surface 307, riding along said surface until the detent 310 engages with the forward depression 308, the lug 309 determining the extent of the movement and the depression 308 coöperating with the detent 310 to hold the parts in the position to which they have been moved. This gives a predetermined extent of rotation to the collar 301 and the movement will be transmitted through the gear 296 and intermeshing pinion 293 to the squared shaft 265 and from it through the bushing 242 to the pressure or feed roller 237, 238. As a consequence the work sheet or sheets on the sub-carriage will be retracted or fed backward continuously to a predetermined extent. It will be understood that when after such movement the finger piece 318 is released, it will be centralized by the springs 319 so that the pawl tooth 317 will disengage from the teeth 302. Thereafter if the finger piece 318 be pushed backward to the Fig. 5 position it will first operate to turn the pawl 314 independently of its carrier and cause the tooth 316 to engage with the teeth 302, after which the toothed collar 301 will be turned reversely until the parts are arrested by the engagement of the rear lug 309 with the detent 310. This movement will be trans-

mitted through the gear 296 and pinion 293 to the squared shaft 265 and the connected feed roller, causing a continuous advance of the paper on the sub-carriage to an extent equal to that to which it had been previously retracted. It will be understood that the operation of the finger piece 318 to advance and retract the paper on the sub-carriage will take place whatever position the sub-carriage may occupy lengthwise of the main carriage and also that such operation will be independent of the line space lever 287 as well as of the finger button 268. The devices connected to and controlled by the finger piece 318 are paper sweep devices corresponding to mechanism commonly termed platen sweep mechanism.

Our prior application aforesaid which has eventuated in Patent No. 1,071,612, granted 20 August 26, 1913 sets forth still another method of advancing the paper on the sub-carriage.

Various features herein disclosed are not claimed but constitute in part the subject-matter of said prior application and of other divisional applications.

What we claim as new and desire to secure by Letters Patent, is:—

1. In a typewriting machine, the combination of a platen, a line spacing wheel connected thereto, a line spacing pawl, an arm on which said pawl is movably mounted, a shaft on which said arm is loosely pivoted, said shaft being arranged at an angle to the platen axis, an actuator fixed to said shaft, hand actuated means for turning said shaft, and automatic means for turning said shaft.

2. In a typewriting machine, the combination of a platen, a line spacing wheel connected thereto, a line spacing pawl, an arm on which said pawl is movably mounted, a shaft on which said arm is loosely pivoted, an actuator fixed to said shaft, means for turning said shaft, a restoring spring for said shaft, a restoring spring for said arm, a stop for said arm, and a stop on said arm for said actuator.

3. In a typewriting machine, the combination of a platen, a line spacing wheel connected thereto, a line spacing pawl, an arm on which said pawl is movably mounted, a shaft on which said arm is loosely pivoted, said shaft being arranged at an angle to the platen axis, a second arm fixed to said shaft, said second arm engaging loosely with said pawl, manual means at one end of said shaft for turning the same at will, and automatic means co-active with said shaft for turning the same.

4. In a typewriting machine, the combination of a platen carriage, a platen, a line spacing ratchet wheel, a line spacing pawl, a carrier to which said pawl is pivoted, a vertical shaft on said carriage on which said carrier is loosely mounted, a pawl actuator

fast on said shaft, a line space handle connected to the upper end of said platen, a crank arm provided with a roller connected to the lower end of said shaft, and a stationary cam with which said roller co-operates during endwise movements of the carriage.

5. In a typewriting machine, the combination of a carriage, a platen, a line spacing wheel, a line spacing pawl, an arm to which said pawl is pivoted, a shaft on which said arm is loosely mounted, a pawl actuator fast on said shaft, and a stationary cam operative to turn said shaft during endwise movements of the carriage.

6. In a typewriting machine, the combination of a carriage, a platen thereon, pawl and ratchet line spacing devices for said platen including a shaft, a cam, a device on said shaft co-operative with said cam to line space the platen during endwise movements of said carriage, a stop co-operative with said device to limit movement of the carriage after said device has been actuated by said cam, and a support for said cam and said stop comprising a bar toothed along one edge, said cam and said stop being slidable along said bar and engageable with the toothed edge thereon and being provided with spring means for maintaining said cam and said stop so engaged.

7. In a typewriting machine, the combination of a carriage, a platen thereon, line spacing devices therefor comprising a shaft, an arm on said shaft, a roller on said arm, and a stationary cam with which said roller co-operates during endwise movements of the carriage to effect a line spacing movement of the platen, said cam being provided with an end portion with which said roller co-operates to prevent further movement of said carriage after the completion of the line spacing.

8. In a typewriting machine, the combination of a carriage, a platen thereon, a line spacing ratchet wheel connected to said platen, a pawl for actuating said ratchet wheel but normally disconnected therefrom, a shaft arranged at an angle to the axis of said platen, connections between said shaft and said pawl for transmitting motion from said shaft to said pawl, a finger piece for actuating said shaft, automatic devices separate from said finger piece for actuating said shaft, and a stop for preventing the disconnection of said automatic devices at the end of their operation.

9. In a typewriting machine, the combination of a platen on which the writing is done, paper feeding mechanism co-operative with the platen to feed paper around the same when the platen is turned, a carriage, a paper feeding device thereon, an operating shaft for said device, a finger wheel on said shaft for turning it to actuate said device to

feed paper, devices also operative on said shaft to effect a continuous advance of the paper to a predetermined extent, and other devices separate from said first recited operating devices and effective on said shaft to advance the paper progressively through line space distances, the paper that is controlled by said paper feeding device and said operating devices being at all times free from control of said paper feeding mechanism, and the actuation of said paper feeding device by said finger wheel and said operating devices being effective to advance paper independently of said platen.

15 10. In a typewriting machine, the combination of a platen on which the writing is done, paper feeding mechanism co-operative with the platen to feed paper around the same when the platen is turned, a carriage,
20 20 a paper feeding device thereon, an operating shaft for said device, devices operative on said shaft to effect a continuous advance of the paper to a predetermined extent, and other devices separate from said first recited
25 25 operating devices and effective on said shaft to advance the paper progressively through line space distances, the paper that is controlled by said paper feeding device and said operating devices being at all times free from
30 30 control of said paper feeding mechanism, and the actuation of said paper feeding device by said devices being effective to advance the paper independently of said platen.

11. In a typewriting machine, the combination of a platen on which the writing is done, paper feeding mechanism co-operative with the platen to feed paper around the same when the platen is turned, a carriage, a paper feed roller thereon operative independently of said platen, a ratchet wheel connected to said feed roller, a co-operating pawl, a pivoted spring pressed arm on which said pawl is pivoted, a pawl stop on said arm, a link connected to said pawl at one end, a rock shaft to which the other end of said link is connected, said rock shaft being mounted on said carriage and being provided with a finger piece for actuating said pawl and returning said carriage, the paper that is advanced by the operation of said pawl and ratchet devices being at all times free from the control of said paper feeding mechanism.

12. In a typewriting machine, the combination of a carriage, a paper feed roller thereon, a ratchet wheel connected to said feed roller, a cooperating pawl, a pivoted spring pressed arm on which said pawl is pivoted, a pawl stop on said arm, a link connected at one end to said pawl, and a rock shaft to which the other end of said link is connected, said rock shaft being mounted on said carriage and being provided with a finger piece for actuating said pawl and returning said carriage, said pawl being also

provided with a finger co-operative with said ratchet wheel to limit the effective action of said pawl thereon.

13. In a typewriting machine, the combination of a platen on which the writing is done, paper feeding mechanism co-operative with the platen to feed paper around the same when the platen is turned, a carriage, a paper feed roller thereon operative independently of said platen, detent devices for said roller, a ratchet wheel connected to said roller, a co-operating pawl provided with two teeth engageable successively with said ratchet wheel, and manually operated means for actuating said pawl member, said manual means comprising a rock shaft mounted on said carriage, and a link connecting said rock shaft with said pawl member, said rock shaft being provided with a finger piece operative to actuate said pawl member and also to restore said carriage, the paper that was advanced by the actuation of said pawl member being at all times free from the control of said paper feeding mechanism. 70 75 80 85

14. In a typewriting machine, the combination of a platen on which the writing is done, paper feeding mechanism coöperative with the platen to feed paper around the same when the platen is turned, a carriage, a paper feed roller thereon, a detent for said feed roller, a finger wheel for turning said feed roller, pawl and ratchet mechanism operative on said feed roller and comprising a handle which is also effective to restore said carriage, and devices for turning said feed roller to effect a continuous advance of the paper to a predetermined extent, the actuation of said feed roller by said finger wheel and said devices being effective to advance the paper independently of said platen, and said paper being at all times free from the control of said paper feeding mechanism. 90 95 100 105

15. In a typewriting machine, the combination of a carriage, a platen thereon, a paper feeding device on said carriage, an operating shaft for said device, a finger wheel for turning said shaft, hand actuated pawl and ratchet mechanism effective to turn said shaft progressively step-by-step, and paper sweep devices effective on said shaft independently of said pawl and ratchet mechanism.

16. In a typewriting machine, the combination of a carriage, a paper feeding roller thereon, a shaft connected to said roller to turn the same, and means for turning said shaft back and forth predetermined extents to effect a continuous advance and a continuous retraction of the paper, said means comprising a toothed wheel connected to said shaft, a pawl carrier pivoted concentrically with said toothed wheel, a double-toothed pawl pivoted on said carrier and provided with a finger piece, and centering means for 120 125 130

8
maintaining said pawl normally in a position in which both its teeth are disengaged.

17. In a typewriting machine, the combination of a carriage; a paper feeding device thereon; and means for moving said device to communicate a continuous advance or retraction to the paper, said means comprising a toothed wheel connected to said device, a pivoted pawl carrier, a double-toothed pawl pivoted on said carrier and provided with a finger piece, and centering means for maintaining said pawl normally in a position in which both its teeth are disengaged.

18. In a typewriting machine, the combination of a carriage; a paper feeding roller thereon; and means for rotating said roller back and forth predetermined extents to communicate a continuous advance or retraction to the paper, said means comprising a toothed wheel connected to said device, a pawl carrier pivoted concentrically with said toothed wheel, a double toothed pawl pivoted on said carrier and provided with a finger piece, spring means for maintaining said pawl normally in a position in which both its teeth are disengaged, and devices for limiting the turning movements of said pawl carrier.

19. In a typewriting machine, the combination of a carriage; a paper feeding device thereon; and means for moving said device predetermined extents to communicate a continuous advance or retraction to the paper, said means comprising a toothed wheel connected to said device, a pivoted pawl carrier, a double-toothed pawl pivoted on said carrier and provided with a finger piece, centering means for maintaining said pawl normally in a position in which both its teeth are disengaged, and limiting devices for said pawl carrier comprising a spring mounted roller detent, and co-operative depressed portions in said carrier.

20. In a typewriting machine, the combination of a carriage; a paper feeding roller thereon; and means for rotating said roller back and forth predetermined extents to communicate a continuous advance or re-

traction to the paper, said means comprising a toothed wheel connected to said device, a pawl carrying lever pivoted concentrically with said toothed wheel, devices co-operative with one arm of said lever to limit its back and forth turning movements, a pawl member pivoted to the other arm of said lever and provided with two oppositely extending teeth at one side of its pivot and with a finger piece at the opposite side of its pivot, and two opposing springs co-operative with said pawl member at opposite sides and normally maintaining both said teeth disconnected from said toothed wheel, said finger piece being effective to turn said member to cause either tooth to engage with said wheel and thereafter being effective to turn said lever on its pivot.

21. In a typewriting machine, the combination of a carriage, a feed roller thereon, a shaft on which said feed roller is mounted, a pinion on said shaft, a gear wheel meshing with said pinion, a toothed wheel connected to said gear wheel, a pawl carrier pivoted concentrically with said toothed wheel, a double toothed pawl member pivoted on said carrier and provided with a finger piece for actuating it and said carrier, and spring means for normally maintaining said pawl disconnected from said toothed wheel.

22. In a typewriting machine, the combination of a carriage, a platen thereon, hand actuated pawl and ratchet mechanism to feed paper step-by-step over said platen, and paper sweep devices effective to sweep the paper over said platen, said pawl and ratchet mechanism being arranged at one end of the platen and said paper sweep devices at the opposite end of the platen.
